UNITED STATES PATENT OFFICE.

BENJAMIN B. ALLEN, OF HANFORD, CALIFORNIA, ASSIGNOR TO HIMSELF,
WILLIAM HENRY WILSON, AND EDWARD WEISBAUM, OF SAME PLACE.

WHIFFLETREE.

SPECIFICATION forming part of Letters Patent No. 448,105, dated March 10, 1891.

Application filed August 30, 1890. Serial No. 363,493. (No model.)

To all whom it may concern:

Be it known that I, BENJAMIN B. ALLEN, of Hanford, in the county of Tulare and State of California, have invented a new and useful Improvement in Spring Attachments for Singletrees, of which the following is a full, clear, and exact description.

This invention consists in a spring trace-holder in the form of a spring attachment for singletrees of novel construction, substantially as hereinafter shown and described, and more particularly pointed out in the claims.

Reference is to be had to the accompanying drawings, forming a part of this specification, in which similar letters of reference indicate corresponding parts in all the figures.

Figure 1 represents a view in perspective of a vehicle or wagon, in part, having shafts provided with my improved spring attachment. Fig. 2 is a side view of said spring attachment in its normal position, and Fig. 3 is a side view of the same attachment under tension or after pull on the singletree or trace connection has been made.

A A indicate the shafts of the vehicle, and B the cross-bar connecting said shafts and which virtually forms the support for the spring attachment to the singletree.

C is the singletree, to the outer ends of which the trace-straps (not here shown) may be attached, as usual.

D is the spring attachment for the singletree and which serves to carry the latter. This attachment is in the form of a double or bifurcated coil spring, of suitably-tempered steel, composed of two coils b b, arranged approximately parallel with each other or side by side and terminating in legs or arms c b. This spring is riveted or otherwise firmly attached by its arms c to the cross-bar or support B, and is arranged to pass back of and over the same by its bent arms d, which incline toward each other and meet in a common center portion e, where the bifurcated construction of the spring terminates. At this meeting portion or end e, which forms the free end of the spring, said spring D is pivoted, as at f, to the singletree, that thus is free to swivel or vibrate from its middle as a center of motion about said pivot f to meet

the requirements of opposite side pulls applied to the ends of the singletree by the trace-straps. Flexible loops or straps s s are fastened to the cross-bar B and receive the ends of the singletree through them to act as stops to the swiveling motion of the singletree and prevent it from vibrating too far and to limit the pull of said tree on the spring attachment. By this construction and application of the spring D not only is the necessary vibratory motion of the singletree retained, but shock to the shoulders of the animal in the shafts is avoided and the full advantage of the spring attachment is obtained. Such spring attachment consequently essentially differs from other spring attachments for trace connections in which the springs are attached to the cross-bar of the shaft or pole and the traces hooked to the ends of the springs.

The invention can be equally well applied to a vehicle having a pole instead of shafts by using the ordinary pivoted doubletree, which is applied to the pole as the support for the spring attachment, and fastening a spring D to each end thereof and pivoting such springs at their closed or free ends to the usual two singletrees—that is, one singletree over each end of the doubletree. As a spring attachment for singletrees the invention, however, and its action are the same as when only one singletree is used and the spring carrying it attached to the cross-bar of a shaft-vehicle, as illustrated in Fig. 1. By means of this spring attachment vehicles may be drawn over rough and uneven roads or streets without sudden jerks, and the animal drawing the load has more perfect control of the vehicle, the spring attachment taking up all the slack that usually obtains in vehicles not having such spring attachment. More work also can be got out of an animal with this attachment, from the fact that there is no shock to the horse's shoulders in passing over rough or uneven roads, streets, or obstructions. It also prevents the racking of carriage-tops caused by the sudden jerking of the vehicle.

Having thus fully described my invention, I claim as new and desire to secure by Letters Patent—

1. In spring attachments for trace connections of vehicles, the combination, with the singletree of a vehicle, of a spring carrying and having pivoted to it at its free end said singletree intermediately of its length and a support for the fast end of said spring connected with the shafts or pole of the vehicle, substantially as specified.
2. In spring attachments for the singletrees of vehicles, the combination, with the singletree, of a bifurcated double-coil tree-carrying spring and a support for the same connected with the shafts or pole of the vehicle, said spring being arranged to pass back of and over or above said support and pivoted at its closed free end to the singletree intermediately of its length, essentially as described.
3. In spring attachments for the singletrees

of vehicles, the combination, with the singletree C, of the bifurcated double-coil spring D, pivoted at its closed free end to said spring, and the cross-bar B or its equivalent spring-support, substantially as described.

4. In a spring attachment for the singletrees of vehicles, the bifurcated or double-coil spring D, composed of two coils b b, arranged side by side in the bifurcated portion of it and having opposite end arms c d, the latter of which close and meet and form the free end of the spring, essentially as shown and described.

BENJAMIN B. ALLEN.
